United States Patent Office.

ALFRED G. BLACK, OF WOOSTER, OHIO.

Letters Patent No. 70,069, dated October 22, 1867.

IMPROVED CAR-REPLACER.

The Schedule referred to in these Letters Patent and making part of the same.

TO ALL WHOM IT MAY CONCERN:

Be it known that I, A. G. BLACK, of Wooster, State of Ohio, have invented certain new and useful Improvements in Portable Railroad Tracks; and I declare the following to be a full, true, and exact description of the same, reference being had to the accompanying drawings, and to the letters of reference marked thereon.

Figure 1 represents a plan view of my track.

Figure 2 is an inverted view of the bed-piece.

Letter A represents common railroad rails, which are secure to the cross-ties B. Letter C represents the bed-piece, to which the shifting rails are attached. This bed is formed of hard wood, so as to be as light and portable as possible, and is furnished with the iron cross-pieces D for the rails to rest on, so as to prevent abrasion. Running at right angles with this bed is a number of slots, F, which extend through the bed, for the purpose of allowing the rails a lateral play. Letter E represents the shifting rails, which are secured to the bed-piece C by means of the bolts g, which extend down through the slots and are secured (as seen in fig. 2) so as to prevent the rail from being raised out of its place. The ends of these rails are bevelled off, so as to allow the locomotive or cars to pass the more freely upon them. When it is necessary a slab-rail, H, may be bolted on to the ends of the shifting rails E, so as to make the rails extend outward more over the main track. By the use of the slotted bed-piece C the rails E can be shifted to the desired angle (when not large) without the trouble or necessity of moving the whole arrangement.

The manner of using my track is as follows: When the locomotive or cars have been thrown off or displaced from the track the bed is placed at such an angle from the track that the cars can be readily drawn or forced upon the shifting rails E. As the ends of the said rails rest upon the main track, (as shown in fig. 1,) the cars can then be readily and evenly replaced upon the proper track.

Having thus described my invention, what I claim, and desire to secure by Letters Patent, is—

I claim the shifting rail E, when provided with the bolts g, in combination with the bed-piece C and slab-rail H, substantially as and for the purpose set forth.

Witness my hand this twenty-ninth day of June, A. D. 1867.

Witnesses:
